R. W. SCOTT,
WELTED KNIT STOCKING AND METHOD OF KNITTING THE SAME.
APPLICATION FILED JULY 23, 1914.

1,128,728.

Patented Feb. 16, 1915.

UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

WELTED KNIT STOCKING AND METHOD OF KNITTING THE SAME.

1,128,728.

Specification of Letters Patent.

Patented Feb. 16, 1915.

Application filed July 23, 1914. Serial No. 852,607.

To all whom it may concern:

Be it known that I, ROBERT W. SCOTT, a citizen of the United States, and resident of Boston, in the county of Suffolk and State of Massachusetts, have invented certain new and useful Improvements in Welted Knit Stockings and Methods of Knitting the Same, of which the following is a specification.

10 My invention relates to knit fabrics having welts or hems and especially to plain knit articles having out-turned welts of the general character illustrated in my Patents Nos. 1,045,620, dated November 26, 1912, 15 and 1,079,267, dated November 18, 1913, and to the art of making such fabrics.

Objects of my invention are to improve the juncture between the welt proper and the attached fabric, and to simplify the 20 making of the fabric.

Figure 1 is a side view of a stocking illustrating one type of my improved article; Fig. 2 is an exterior view illustrating the points of attachment of the welt and of the 25 top and the body according to my invention; Fig. 3 is a diagram illustrative of a segment or section of needles of a machine, in aid of explanation of the method. Figs. 4 to 7 are diagrams illustrative of the formation 30 of the first few courses of the welt.

My improved article may be composed of flat or tubular fabric having therein needle wales *a* and *b* separated by the usual sinker wales. I may provide an integral welt *W* and top *T*, for one instance, upon a circular knit or seamless stocking such as that shown in Fig. 1, having a leg *L*, a foot *F*, and a heel and toe of the usual form, the leg *L* consisting of fabric of any desired number 35 of needle wales in width, the top *T* having therein fewer needle wales and the welt *W* having as many needle wales as the top. The welt *W* is of the genus illustrated in my said patents, comprising plain fabric having 40 needle wales of which the back or loop side lies outward, the face or wale side lying within a tubular fold continuous with that part of the article to which it is attached, certain loops at or near the beginning of the 45 welt being withheld upon the needles, and subsequently attached where the welt fabric merges into the article by loops engaging the withheld loops, the course containing 50 said engaging loops being hereinafter referred to as a uniting course. In my ap- 55 plication Serial No. 823,121, filed March 7, 1914, (now Patent No. 1,113,166, dated October 6, 1914) I have described and claimed an improvement over said patented constructions comprising a welt having as many 60 needle wales as the attached fabric, the withheld loops being provided in needle wales standing between and corresponding to the sinker wales of the attached fabric. My present invention provides another species 65 of the genus described and claimed in said application.

Referring now to Fig. 2, I provide a welt *W* having as many needle wales *a* as the attached fabric *T* has wales *b*, the withheld loops *w* for uniting the initial part of the welt to the fabric *T* being provided in wales corresponding to the wales *b* of the fabric *L*, which wales *b* stand between and correspond to the sinker wales between wales *a* 75 of the welt fabric *W*. I begin the welt, referring now to Fig. 3, by feeding an initial yarn 1 to the needles *a*, said yarn not being taken by the needles *b*, but passing at their backs. The first course will then lie when 80 viewed in plan as shown in Fig. 4. I may as described in my Patent No. 1,094,347, dated April 21, 1914 maintain the said yarn 1 of the first course under stress in the manner therein described and claimed. 85 Having applied a yarn 1 to the recurrent needles *a* among the whole series of needles, I now apply a yarn 2 to the needles *b* only, which are the remaining needles, if necessary placing said yarn under stress in the 90 same manner as the course of yarn 1 to cause it to pass behind the position of the needles *a*. The yarn structure lying upon the needles will now be that illustrated in Fig. 5. The needles *b* holding the loops of 95 the yarn 2 are now retired to a position permitting the needles *a* to knit and cast off over their heads, the said needles *b* holding their loops *w* of the course 2. Knitting for the fabric of the welt may now proceed upon the needles *a* only, as indicated in Figs. 6 and 7. The described operations have resulted in engaging the yarn of course 2 at the loops *w* with the initial yarn 1, but no loop of the yarn of course 2 is taken in the 100 wales *a*, which are initiated as shown in Figs. 2 and 6 by knitting through the loop originally taken by said needles *a* of the yarn 1. With respect to the article of manufacture, the withheld loops thus occur in 110

one course, that of the yarn 2, in which the needle-loops w pass through sinker-wales of the welt fabric while the beginning of the welt fabric occurs in the wales a of course 1. A distribution of strain between the yarns of courses 1 and 2 results from this procedure. Knitting for the entire fabric of the welt now proceeds in the manner shown in Fig. 7, for instance until the course 30 as shown in Fig. 2 is reached, whereupon the needles b withholding the loops w are caused to take yarn and knit, together with the needles a , to form the uniting or welt casting-off course Z. This course will contain loops y penetrating the loops in the wales a of the course 30 and loops z penetrating the loops w of course 2.

In many situations, especially to form a cuff or top of a man's stocking or sock such as that shown in Fig. 1, it is desirable that the fabric T for the cuff or top should contain fewer wales and be formed of heavier yarn while retaining the same or nearly the same diameter as the leg. I may therefore now proceed, to form the structure described and claimed in my said application Serial No. 823,121, to suppress the wales a , while providing a structure to lock the loops y in the said wales against raveling and releasing the terminal loops of the welt fabric W, by knitting one or more courses X in the wales a only, permitting the yarn of said course or courses X to pass behind loops of the wales b , as by again operating the needles b to hold the loops z and to retire to a position permitting the yarn of course X to be passed over the heads of said needles b . The last course X having been knit, the needles are operated to cast off the loops w in said course. These loops are the terminal loops of all the wales a , which, as described in my said application, are thrown forward between the other needles, so that when the needles b are again operated in course 33, the yarn of said course 33 will engage the loops w , which are thus passed through the sinker wale between adjacent needles b toward the face of the fabric, to form an efficient lock to prevent raveling of the loops w and those behind them. The top fabric T may now be knit as described in my said application upon the needles b , beginning at the course 33, with the exchange of the yarn for a heavier yarn, which will again be replaced by a lighter yarn at the end of the top T, for instance in the course 121, Fig. 2. At the end of the fabric T, the needles a will be again introduced to knit normal fabric upon the full number of needles so far employed for the leg L. This introduction results in the eyelet holes h , shown as occurring between courses 120 and 121. As I have explained in my said application, carrying the heavy yarn past the course in which the needles are intro-

duced to form the fabric L results in decreasing the size of the eyelet holes h , by reason of the greater stiffness of the yarn of the top fabric T.

In connection with Fig. 3 I have illustrated merely to indicate capacity for differently operating particular needles short jacks j for the needles b and longer jacks j' for the needles a . The operations described when performed by machine require the needles b to be retired from action while holding their loops during knitting upon the remainder and require the needles a to be capable of being operated so as not to take the yarn, or as to cast off and so retire (or to cast off in each course) during normal knitting upon the remainder. These operations may be performed in an independent needle knitting machine by suitably operating the jacks of different lengths selectively at required times.

What I claim is:

1. In a knit fabric, a portion forming a welt and a portion integrally attached thereto, said welt portion having a course 90 subsequent to the initial course all of the needle-loops of which are penetrated by a course of the attached fabric.

2. In a knit fabric, an integral welt having an initial course comprising the initial 95 loop of each needle-wale of the welt fabric, and a course of yarn free of said needle-wales engaging said initial course and having loops attached to another portion of the fabric.

3. In a knit fabric, a welt, said welt having an initial course, and a subsequent course comprising withheld loops in engagement with said initial course only, the needle wales of the welt beginning at loops 105 of the initial course, and a uniting course drawn through said withheld loops and the terminal loops of the needle wales of the welt.

4. A knit fabric having an integral out-turned welt, said welt being joined to adjacent fabric by withheld loops in a course subsequent to its initial course and by its terminal loops, the needle wales of said welt all extending from loops of a course other 115 than that containing said withheld loops.

5. In a knit fabric a welt having needle-wales and sinker-wales and an attached portion having needle-wales corresponding to sinker-wales of the welt, a uniting course 120 having one needle loop in each needle wale of both of said parts, that loop of said uniting course occurring in a needle wale of the attached portion engaging a withheld loop passed through a sinker-wale of the welt 125 fabric.

6. In a knit fabric an integral welt united to the attached fabric by a course of needle loops in wales suppressed in nearby courses, said loops being locked against raveling, 130

said uniting course having other loops in engagement with a course of the welt engaging the initial course thereof only.

7. In a stocking, a top having a certain number of wales, a welt having the same number of wales, and a uniting course having as many loops as there are wales in both fabrics, said loops alternately engaging withheld loops in a course of the welt 10 subsequent to the initial course and in engagement with said initial course only, the remaining loops of said uniting course penetrating the terminal loops of the welt fabric.

8. The method of forming plain-fabric knit articles having an integrally united welt which comprises first forming an initial course into loops at recurrent instruments only of a series of instruments; thereafter forming a subsequent course having 20 loops at the remaining instruments of said series of instruments only; thereafter knitting successive courses of welt fabric of loops knit at those instruments which took the first course only; thereafter forming a 25 uniting course having loops penetrating all of the loops of said subsequent course and the terminal course of welt fabric, and then

knitting fabric in continuation of said uniting course.

9. The art of knitting a welt and an attached portion of a plain fabric knit article with the aid of a series of hooked instruments such as knitting needles, which comprises placing an initial course in the hooks of recurrent instruments of said series, 30 thereafter placing a second course in the hooks of the remaining instruments and causing the second course to pass at the backs of said recurrent instruments, withholding the loops of said second course at 35 said remaining instruments and then knitting fabric for a welt at said recurrent instruments; and thereafter forming a uniting course at all of said instruments and knitting an attached portion of the fabric 40 in continuation of loops of said uniting course.

In testimony whereof, I have signed my name to this specification in the presence of two subscribing witnesses.

ROBERT W. SCOTT.
